UNITED STATES PATENT OFFICE.

HENRY R. REISCHMANN, OF NEW YORK, N. Y.

DESIGN FOR A COUNTER-STOOL FOOT-REST.

48,010.

Specification for Design.

Patented Oct. 19, 1915.

Application filed June 21, 1915. Serial No. 35,466. Term of patent 3½ years.

To all whom it may concern:

Be it known that I, HENRY R. REISCHMANN, a citizen of the United States, residing at New York, in the county of the Bronx and State of New York, have invented a new, original, and ornamental Design for Counter-Stool Foot-Rests, of which the following is a specification, reference being had to the accompanying drawing, forming part thereof, in which—footrest applied to a counter stool and Fig. 2 is a plan view of the same, showing the counter stool in horizontal cross section.

In the figures, a represents the leg or pedestal of the counter stool, b the foot rest, c the clamping portion thereof and e a leg or support provided for the foot rest.

I claim:

The ornamental design for a counter stool foot rest, as shown and described.

HENRY R. REISCHMANN.
